UNITED STATES PATENT OFFICE.

JOHN D. GUIS, OF SEATTLE, WASHINGTON, ASSIGNOR OF ONE-HALF TO L. W. HARKINS, OF TACOMA, WASHINGTON.

POSITIONING APPARATUS FOR HEADLIGHTS.

Application filed June 30, 1925. Serial No. 40,505.

This invention relates to apparatus for positioning the spot and headlights of automobiles; and its object is the provision of inexpensively constructed and conveniently 5 adjustable apparatus of this character.

The invention consists, generally, in a pair of companion members having indicating marks thereon, and in means for regulating the members to locate elevations and horizontal 10 positions of the markings thereon predeterminedly.

The invention further consists in the novel construction, adaptation, and combination of parts hereinafter described and claimed.

15 In the accompanying drawing,—

Figure 1 is a perspective view of apparatus embodying the present invention shown applied to the wall of a building; Fig. 2 is a vertical section taken substantially on line 20 2—2 of Fig. 1; and Fig. 3 is a perspective view of a portable stand upon which the positioning devices are mountable.

In said drawing, the reference numerals 5 and 5¹ represent two complementary 25 boards of wood or other suitable material.

As shown, these boards are of rectangular 30 shape, disposed in overlapping relation, and are connected with each other for relative horizontal movement as by means of clips 6 and 6¹.

Said clips are secured to the respective 35 boards and have offset guiding arms 7 and 7¹ to afford slide-ways for the complementary boards. Provided upon each board are guide marks, herein shown as a horizontal 40 line 8 and a vertical line 9 disposed in crossed relation with respect to each other, the horizontal lines 8 of both boards being aligned with each other. As shown, said 45 boards are suspended from a horizontally disposed bar 10 which, in Figs. 1 and 2, is represented as being rigidly secured to a wall 50 W as by screws or an equivalent fastening means.

When it is desired, however, to use the apparatus in different situations said bar is secured to a portable frame such as that 55 illustrated in Fig. 3, for example, wherein the bar designated by 10¹ is rigidly secured to the post members 11 of the frame which is indicated generally by 12.

The bar 10, as shown, is formed to provide along its upper edge a ridge 13 which is engageable in the hooked upper portions 14 55 of carriers 15, one or more for each board.

Each carrier 15 is provided with a sight aperture 16 through which may be seen scales, or graduations, 17 and 17¹ (Fig. 1) provided upon the bar 10.

The divisions of each of said scales are 60 denoted by numerals as, "24," "26," "28," etc., which designate twice the distances, in inches, the respective marks of scales are from a medial line—indicated by dotted line O in Fig. 1, and the actual distances between 65 correspondingly designated scale marks of both scales—for example, the scale numerals "30" upon the bar 10 will be fifteen inches from the medial line O and thirty inches from each other.

70 Each of the carriers 15 is provided with a slot 18 to receive the loop of a flexible strap S having the end of one of its folds, as 19, secured to an attachment 20 of the respective board; the end of the other fold, 21 being secured to a slide 22 which is mounted upon the respective fold 19.

75 Provided upon each slide 22 is a clamping lever 22¹ for engaging the respective slide to the associated strap fold 19 to register with a predetermined scale marking of a series of graduations 23 provided upon the strap fold 19. The graduation marks of such straps are arranged to indicate the proper regulation of the straps to suspend 80 the boards to cause the horizontal marks thereon to be at selected elevations above the floor F—that is to say, when the slides are respectively located to register with 85 graduations, as indicated by "40" for example, on the straps whereupon the latter will be adjusted to suspend the boards at an elevation such that the lines 8 will in this 90 instance be forty inches above the floor F. The straps and the connections of the same 95 with the boards and the carriers 15 are such that the relative positioning of the carriers with respect to the scale marks 17, 17¹ will indicate the separation of the vertical marks 100 9. To verify the correctness of the horizontal setting of the boards, a series of scale markings 24 may advantageously be provided upon the rear board 5¹ to be readable with respect to the edge 25 of the other board 5.

105 The invention so far described is utilized for positioning the slant or inclination of the headlights of an automobile, the boards 5 and 5¹ being regulated in the manner above 110 described to locate the lines 8 and 9 to cor-

respond with the elevation and distance apart of the centers of the projected light beams when the headlights are tried without lenses and are located at a distance, say, of twenty-five feet from the boards.

Replacing the lenses upon the headlights, the top of the light-ribbon, as is conventionally termed the main portion of the composite beam from both lamps, should illuminate a region on the boards entirely below the horizontal lines 8. If such a condition does not obtain the lamps are tiltably adjusted to cause such beam to conform to such a requirement.

15 For determining the vertical angular position of the spotlight of an automobile to have its beam of light pass beneath a horizontal line at a predetermined distance—as thirty feet, for example—in front of the 20 spotlight, the lines 8 may be utilized to indicate the maximum height of the spot beam by suitably raising or lowering the same through the instrumentality of the strap devices as hereinbefore explained.

25 In employing the boards for testing the spotlight beams it is requisite that a table or schedule of elevations of the board-marks 8 with respect to the elevation of the spot-light for different automobiles should be provided 30 and which, for instance, may be in the ratio of about five to six; hence, if the height of the focal axis of the spotlight at the car is forty-eight inches above the floor, the maximum height of the spotlight beam at its intersection by the boards should be approximately forty inches.

To obviate the inconvenience of adjusting the boards vertically for regulating a spotlight other means are advantageously employed such for example as a rod 26 (Fig. 1) 40 having at its upper end a hook 27 which is engageable over the ridge 13 of the bar 10, said rod having thereon graduations 28 which are located at elevations suitable to 45 determine proper downward slant of the beam of a spotlight being tested, the denominating characters upon the rod being arranged to indicate the maximum heights of the beam of light projected thereon at 50 the respective graduations in terms of the spotlight's elevation on the car.

What I claim, is,—

1. In apparatus of the character described,

complementary members having markings thereon and arranged for relative horizontal movement, a rigid support including a horizontal bar element, and adjustable devices depending from said bar element for suspending said members to position the markings thereon at selective elevations. 60

2. In apparatus of the character described, two board members having horizontal and vertical markings thereon, means for slidably connecting said members together for relative horizontal movement, means for supporting said members to have the horizontal marks thereon at different elevations selectively, said means being adjustable for regulating the members to have the vertical marks thereon at selective distances apart, and 70 means for suspending said supporting means.

3. In apparatus of the character described, complementary board members having markings thereon, devices for connecting said members for relative adjustments, a horizontal bar member, means for supporting said bar member in a horizontal position, and means depending from said bar for supporting the board members at different elevations selectively, said means comprising for each board member a carrier slidable endwise of said bar member, an attachment for the respective board, a strap engaging the carrier and the attachment, and means for 80 regulating the effective length of the strap. 85

4. In apparatus of the character described, complementary board members having markings thereon, devices for connecting said members for relative adjustments, a horizontal bar member, means for supporting said bar member in a horizontal position, said bar being provided with graduations thereon, and means depending from said bar for supporting the board members at different elevations selectively, said means comprising for each board member a carrier slidable endwise of said bar member and with respect to the graduations thereon, a strap engaging the carrier, means for attaching 100 an end of the strap to the respective board member, and means for regulating the effective length of the strap. 95

Signed at Seattle, Washington, this 2nd day of June, 1925.

JOHN D. GUISS.
